UNITED STATES PATENT OFFICE.

WILLIAM EDWIN GRADWELL, OF CLAYTON BRIDGE, ENGLAND.

WARP STOP-MOTION FOR LOOMS.

1,245,705.

Specification of Letters Patent.

Patented Nov. 6, 1917.

Application filed September 2, 1914. Serial No. 859,778.

To all whom it may concern:

Be it known that I, WILLIAM EDWIN GRADWELL, a subject of the King of Great Britain and Ireland, and resident of Clayton Bridge, in the county of Lancaster, England, have invented a new or Improved Warp Stop-Motion for Looms, of which the following is a specification.

This invention refers to and consists of a new or improved warp stop motion for looms, the object of the invention being to provide a simple and compact arrangement of mechanism adapted for use with a small or a large number of warps.

According to the invention, the improved stop motion consists of a number of wire drop pins or the like, one for each warp thread and each preferably similar in shape to a hair pin. These pins are arranged to lie with their limbs to right and left of a fixed or stationary bar extending across the loom. Below such bar is a further fixed or stationary bar separated only from the upper bar for a slight distance. In the space thus provided between the fixed bars is a further bar designed to slide to and fro between the fixed bars. This sliding bar at each end engages a slot in a lever arm. Each lever arm is secured to a shaft common to both, and, under the partial rotation of such shaft first in one direction and then in the other, the lever arms move the sliding bar to and fro between the fixed bars.

The oscillatory motion is imparted to the said bar-operating shaft by means of an eccentric or crank on the loom tappet shaft, and also by means of a connecting rod and a slip friction coupling on the said bar-operating shaft. In connection with such slip friction coupling is a part which, on the coupling slipping, moves to act upon loom-stopping mechanism.

The said drop pins, when the warp threads are intact and at their normal tension, lie with their lower ends slightly above the space in which the sliding bar moves, but as soon as a pin falls, owing to the breaking or undue slackening of a warp thread, its limbs come into the path of the sliding bar and obstructing such bar cause it to remain stationary. In thus being held stationary,

the bar, in turn, holds the lever arms and their shaft stationary, whereupon the operative part of the slip friction coupling, by continuing to move under the action of the eccentric on the tappet shaft, causes the coupling to slip, and, through the said part which operates upon the loom-stopping mechanism, stops the loom.

In restarting the loom after repairing the broken warp and after the pin is again held clear of the sliding bar, the parts of the slip friction coupling resume their normal relative positions with the next oscillation of the shaft, when the sliding bar again moves to and fro. For looms weaving a large number of ends, there will be two or more sets of stationary bars, and two or more sliding bars.

Upon the accompanying drawings, 70
Figure 1 illustrates a front elevation, partly broken away,

Fig. 2 a longitudinal sectional elevation on line $x-x$ (see Fig. 3).

Fig. 3 a top plan, and 75
Fig. 4 a further plan on line $y-y$ (see Fig. 2),

Fig. 5 a transverse sectional elevation on line $z-z$ (see Fig. 1), and

Fig. 6 a left hand end elevation of one 80 example of the improved loom warp stop motion, there being four pairs of stationary bars and two sliding bars.

Fig. 7 illustrates a side elevation of the loom stop mechanism, and, in conjunction 85 with Fig. 5, illustrates the connection between such mechanism and the slip friction coupling.

Fig. 8 illustrates a side sectional elevation of the slip-friction coupling shown in Figs. 90 1 to 6.

Fig. 9 illustrates a front elevation of a further modification of the slip friction coupling.

Fig. 10 illustrates one of the warp drop 95 pins.

Referring to Figs. 1 and 2 of the drawings, a, a are the fixed or stationary upper bars, and b, b are the fixed or stationary lower bars, while c, c are the sliding bars. 100 The bars a, a, b, b are almost equal in length to the width of the loom and at their ends are

supported by brackets d' , d^2 , d^3 , the brackets d' , d^3 being preferably in two parts to allow of adjustment to suit the width of loom.

The bars a , a , b , b are spaced apart at 5 each end by lugs e' , e^2 formed in one with transverse members e^3 , e^4 respectively, the transverse members e^4 being formed in one with the brackets d^2 , d^3 , see Figs. 2 and 5. The sliding bars c , c are joined by cross-10 pieces c' in one with each of which is a pin c^2 . In said brackets d' , d^2 d^3 is journaled the shaft f , and upon such shaft are secured the lever arms g' and g^2 , the latter being slotted (see Fig. 6) and comparatively small15 and free to move to and fro within a recess in the members e^3 , e^4 at the right hand end of the apparatus, while the former is comparatively large and hollow, see Figs. 2 and 8. The lever arm g^2 by its slot, and the lever20 arm g' by means of a groove g^3 in one side engage the pins c^2 on the cross-pieces of the sliding bars. Loose upon the shaft f and lying between the hollow boss of the lever arm g' is a further lever arm h , see Figs.25 2 and 8. In the periphery of the boss of such lever arm h is a curved or segmental recess h' , while normally pressing into such recess is a wheel i carried by a spindle j . This spindle projects at its free end through30 a hole in the end of the lever arm, and between the end of the lever arm and a shoulder on the spindle is a spring j' , which yieldingly holds the wheel i in frictional contact with the lever arm boss, the contact being35 such that, with nothing to obstruct the movements of the lever arms g' , g^2 , they and the bars c , c are moved to and fro when the lever arm h oscillates. The said lever arm h is connected by rod k , see Fig. 5, with the40 eccentric l on the loom tappet shaft m , which latter, when in motion, affords a continuous oscillatory motion to the lever arm h .

The brackets d^1 , d^2 are preferably joined45 to each other at their lower parts by side pieces d^4 , which serve to inclose the lever arm g' , see Figs. 1 and 4. The brackets d^2 and d^3 are formed with extensions d^5 , in which are supported rails d^6 for supporting the warp fore and aft of the bars a , a , see50 Fig. 5.

Placed loosely on each warp thread is a drop pin n similar in shape to a hair pin, see Fig. 10. Each drop pin lies with its limbs55 to right and left of the bars a , a above the level of the plates c , c , see Fig. 5.

To the bracket d^2 is pivotally connected a lever o which at its free end rests upon the bracket d' , see Fig. 2, and at a point60 in its length over-lies the projecting end of the spindle j in the lever arm g' , see Fig. 2.

At its free end the lever is connected by a wire or cord p , passing around pulleys p' on the loom frame, with the loom stop mech-

anism, see Figs. 2, 5 and 7. The loom stop 65 mechanism may be of any suitable kind but consists preferably of a weighted lever q , carried pivotally and pendulously from a bracket r , adjustably secured to the loom stopping and starting lever s . 70

When the loom is in motion and the warps intact, the lever q assumes the position shown in full lines, *i.e.*, with the end of its shorter arm below the shoulder s' on the bracket r , but on the cord p being pulled, 75 the lever q assumes the position shown in broken lines. In such position the weighted end of the lever q lies in the path of the loom slay d^8 , and on being struck by the slay during its next forward movement, the lever q 80 serves to release the lever s from its retaining catch which thereupon moves in the usual way to stop the loom. On again starting the loom, the lever q by the jar of the lever s , automatically loses its abutment 85 with the shoulder s' and resumes the full line position.

The widths of the bars c , c and their motion are such that both limbs of the pins n must drop before they can have any effect 90 on the bars c , c .

Assuming the drop pins n to be in position on the warp threads and the loom in motion, the eccentric l on the tappet shaft m imparts a rocking motion to the lever arm h 95 which in turns rocks the shaft f through the lever arm g' and spring-pressed wheel i . The bars c , c are normally oscillated by the arm g' but immediately a warp thread breaks its pin n is dropped to form a bridge 100 between the two respective stationary bars a , b thereby constituting an obstruction in the path of the sliding bars c , c and arresting the motion of the same. The motion of the arm g' and consequently of the shaft f 105 is simultaneously arrested, which causes the wheel i to ride up the cam surface h' carrying with it the plunger j . The latter is projected against the lever o so as to swing it about its pivot, the free end of said lever exerting a pull on the cable p which is transmitted to the member q so as to raise it into position to engage the loom slay as before described. 110

Referring to Fig. 9, the slip friction coupling therein shown consists of the two collars v' , v^2 , one fast and the other loose on the shaft f and the adjoining ends of the collars being inclined to the shaft f and being held in frictional contact by a spring f' . 115 Upon a warp breaking and a pin n arresting the motion of the bars c , c and the lever arms g^3 , the continued motion of the collar v^2 by the eccentric l' serves to cause the collar v' , owing to the inclined faces, to move 120 endwise, and operate upon the lever u^2 and through such lever and a wire or cord p actuate the loom stopping mechanism. As in 125

the case of the lever u in Fig. 9, the lever u^2 may normally rest against a stop u^3 to avoid contact with the collar v^2 when not being operated thereby.

5 The bars b , b may be dispensed with but to prevent risk of the drop pins being bent it is preferred to use the bars b , b .

To allow of the drop pins being easily handled and also readily seen when 10 dropped, they may each have an extension slightly bent outward at its top end. And to facilitate making the extension, the drop pin may be formed by bending the wire of one limb back upon itself and upward 15 above the fork, see Fig. 10.

What I claim is:—

1. A warp stop motion for looms comprising, in combination, drop-pins or detectors of hair-pin formation, upper and lower bars 20 connected to rigid supports, intermediate reciprocating bars slidably mounted on said supports, a rock shaft also mounted on said supports and having a lever arm loosely mounted thereon, means to oscillate said 25 arm, cam surfaces on the boss of said oscillatory arm to impart the oscillatory movement thereof, through spring-pressed means, to the rock shaft, which in turn imparts movement to the reciprocating bars, means 30 to communicate the motion due to the relative displacement of the boss and rock shaft connection, due to the cam surfaces, to the loom stop mechanism, substantially as described.

35 2. A warp stop motion constituting a self-contained fitting, comprising, in combination, end brackets to which are secured a series of upper and lower stationary bars, and bars arranged fore and aft to support the 40 warp threads, upon which are wire detectors, a series of intermediate reciprocating bars slidably mounted on said brackets, a rock shaft also mounted on the brackets with crank arms interconnected with the reciprocating 45 bars, a slip-friction coupling comprising angularly fixed parts on the rocking shaft and a rocking lever having cam faces to engage said angularly fixed parts, means to impart the relative motion of the slip-friction coupling members to the loom stop 50 mechanism, substantially as described.

3. A warp stop motion, comprising, in combination, end brackets to which are secured upper and lower bars, intermediate 55 reciprocating bars sliding on said brackets, drop-pins supported above said bars, means for transmitting motion to the movable bars, said means comprising a rock shaft mounted in the brackets, lever arms fast on said shaft and engaging the ends of the movable bars; a lever arm loose on the shaft and having a boss with a recess in its periphery, a spring-pressed spindle capable of radial movement 60 relative to the shaft, one end of which enters

said recess in the boss to normally couple 65 the lever arm to the rock shaft, while the other end lies clear of a second lever pivoted to a fixed part of the machine, said spindle being adapted to ride up the recess in the boss of the lever arm when the reciprocating bars are arrested, so that the opposite end of 70 said spindle actuates the second lever, means to impart the movement of the second lever to the loom stop motion, and means to oscillate the lever arm, substantially as described. 75

4. A warp stop motion for looms having drop pins of hair pin formation, a series of pairs of stationary bars, means for rigidly positioning said bars, one bar of each pair being supported at a slight distance below 80

the other bar, intermediate bars movable in a straight path and supported on the supports for the stationary bars, all the bars being positioned so that the drop pins, when supported by the warp threads, lie across 85 said bars and normally above the level of the movable bars, means for supporting the warp threads fore and aft of the bars, means for transmitting motion to the movable bars, said means comprising a shaft mounted in 90 the same supports which support the bars, a slotted lever arm fast on such shaft and engaging one end of the movable bars, a further and hollow lever arm with grooves in one face engaging the other end of the 95 movable bars, a lever arm loose on the shaft, having a boss with a segmental recess in its periphery, a spindle within the hollow lever arm, a wheel carried by said spindle and a spring whereby the wheel yieldingly engages the recess in the said boss, the said hollow lever arm having a hole in its free end through which the said spindle projects, an eccentric on said loom shaft, and a rod 100 connecting the eccentric to the lever arm 105 having a recessed boss, a lever arm pivoted to one of the supports of the bars and overlying the end of the hollow lever arm and means for supporting the free end of such lever arm normally clear of the spindle, a 110 further lever connected to such lever arm and adapted to be moved into and out of the path of the slay thereby, substantially as described.

5. A warp stop motion for looms, comprising, in combination, upper and lower bars connected to rigid supports and over which pass the warp threads, having thereon drop pins or detectors of hair-pin formation, intermediate reciprocating bars slidably 115 mounted on said supports, a rock shaft also mounted on said supports and having a lever arm loosely mounted thereon, means to oscillate said arm, cam surfaces on the boss of said oscillatory arm to impart the oscillatory movement thereof, through spring-pressed means, to the rock shaft, which in turn imparts movement to the reciprocating bars, a 120

lever pivoted to one of the supports of the bars and overlying the lever arm on the rock shaft and adapted to be actuated by the relative movement of the aforesaid oscillatory arm and spring-pressed means, loom starting and stopping mechanism and means between the free end of said arm and said mechanism whereby on the lever being raised, the loom stopping mechanism is moved into a posi-

tion for being operated upon by the loom to slay, substantially as described.

In witness whereof I have hereunto set my hand in the presence of two witnesses.

WILLIAM EDWIN GRADWELL.
